UNITED STATES PATENT OFFICE

2,000,846

CURTAIN PROTECTOR

Agnes Juelson, Chicago, Ill.

Application June 7, 1934, Serial No. 729,473

5 Claims. (Cl. 156—33)

When a window sash is raised, the window curtains often blow outwardly through the window, an occupant of the room thereby being deprived of the privacy which the curtains afford. Moreover, the curtains are soiled under the circumstances mentioned. If there happens to be a screen in the window, the curtains are blown against the screen, to their damage.

One object of the invention is to provide novel means for preventing the curtain from blowing outwardly. Another object of the invention is to improve the barrier, as to its strength, its capacity for expansion, to fit different windows, and as to its mounting. Other objects will be made manifest hereinafter. Preferred forms are shown, but a mechanic, working within the scope of what is claimed, may make changes, without departing from the spirit of the invention.

20 In the drawings:—

Fig. 1 is an elevation showing a window frame equipped with the device forming the subject matter of this application;

Fig. 2 is a cross section on the line 2—2 of Fig. 1, the barrier being closed;

Fig. 3 is a cross section on the line 2—2 of Fig. 1, the barrier being open;

Fig. 4 is an elevation of one member of the barrier, parts being broken away and parts being in section;

Fig. 5 is a section on the line 5—5 of Fig. 4;

Fig. 6 is a section on the line 6—6 of Fig. 4;

Fig. 7 is an elevation showing a window frame provided with a modified form of the invention;

Fig. 8 is an elevation showing a modification of the barrier;

Fig. 9 is a section on the line 9—9 of Fig. 8;

Fig. 10 is a top plan of the structure shown in Fig. 8;

Fig. 11 is a fragmental elevation showing a modification in the filler;

Fig. 12 is an elevation showing a modified form of the invention, parts being broken away;

Fig. 13 is a top plan of the structure shown in Fig. 12;

Fig. 14 is a transverse section on the line 14—14 of Fig. 12;

Fig. 15 is a fragmental rear elevation;

Fig. 16 is a front elevation with parts broken away, the view illustrating a further modification; and

Fig. 17 is a top plan of the structure shown in Fig. 16.

Referring to Figs. 1 to 6, the numeral 1 marks a window frame including a sill 2, a lintel 3,

and vertical jambs 4. The curtains 5 and the drapes 6 usually are carried by a rod 26 on the lintel 3.

Carrying strips 7 are attached to the inner surfaces of the jambs 4. U-shaped hangers 8 are secured to the carrying strips 7. Hinge pins 9 connect the hangers 8 with hinge lugs 10 on outer barriers 11. The outer barriers 11 are hinged at 12 to inner barriers 14. The inner barriers 14 may be connected by any sort of latch mechanism, such as a chain and pin 15.

The barriers 11 and 14 are constructed alike and a description of one of them will answer for all.

Referring to Fig. 5, each carrier comprises frame members 16 and 17 which are U-shaped in elevation. The frame members 16 and 17 comprise side pieces 18, top pieces 19, and bottom pieces 20. The top pieces 19 are slidably overlapped on each other for relative longitudinal movement. The same observation holds true with respect to the bottom pieces 20. This construction permits the area of the barrier to be changed, to accommodate window frames of different widths. The top pieces 19 have outstanding flanges 21. The bottom pieces 20 have outstanding flanges 22. The side pieces 18 have outstanding flanges 23. The side pieces 18, the top pieces 19, and the bottom pieces 20 have holes 24. The holes 24 of the bottom pieces 20 can be brought into registration, as the barrier is expanded or narrowed and the holes in the top pieces 19 bear the same relation to each other. The filler 25 may be made of ribbon, cloth, or other flexible material, laced through the holes 24. Any kind of a filler can be used, however.

The outstanding flanges 21 of the top pieces 19 have registering slots 27. The outstanding flanges 22 of the bottom pieces 20 have similar slots 28. In the slots 27 and 28, respectively, are mounted holding devices 29 and 59, such as bolts. When the barrier is expanded or contracted to the desired size, the holding devices 29 and 59 are tightened up, to keep the barrier at the size to which it has been adjusted.

An ornament 30, preferably in the form of a vertical plate, is provided, and has an outstanding wing 31 (Fig. 5) disposed on top of the uppermost flange 21 of the corresponding top piece 19. The holding device 29 passes through the wing 31. As the barrier is expanded or contracted, the holding device 29 can be slid in the slots 27, and thus the ornament 30 may be disposed symmetrically with respect to the barrier, regardless of the

size to which the barrier has been adjusted. The member 30 is a reenforcement, as well as an ornament.

When the barriers 11 and 14 are in the closed position of Fig. 1, they prevent the curtains 5 and the drapes 6 from blowing out the window, or against the screen, if there is a screen in the window frame 1. If no curtain 5 is provided, the barriers 14 and 11 afford privacy, and if the curtain is used, added privacy is possible, since the curtain cannot blow out the window. The barriers 11 and 14 may be opened inwardly and closed together, as in Fig. 5, so as to form an angle with the window frame. In the angles thus formed, the curtains 5 and the drapes 6 may be lodged, and they will not blow out the window, if the window is open, or obstruct the view if the window is closed.

In Fig. 7, parts hereinbefore described have been designated by numerals previously used, with the suffix "a". But two barriers 11a are used, instead of four as in Fig. 1, and the hangers 8a are secured directly to the jambs 4a of the window frame.

In the modification shown in Fig. 8, the barrier embodies a frame 32, having outstanding flanges 33. The filler 34 may be laced through holes 35 in the frame, as hereinbefore described. The top and bottom flanges 33 of the frame 32 are provided, near to the inner edge of the frame, with elongated slots 36, receiving projecting fingers 37 on arms 38 that extend outwardly through holes 39 in the vertical flanges of the frame 32. At their outer ends, the arms 38 have hinge pintles 40 engaged with the ends of a hanger 41, like the hanger 8 of Fig. 5.

The barrier includes an extension 42, which may be of lattice construction, as shown at 43. The extension 42 has hooks 44 at its upper and lower ends, the bills of the hooks being parallel to the extension 42 as shown in Fig. 9. The hooks 44 are slid over the projecting ends of the arms 38, and by substituting extensions of different sizes, the area of the barrier may be adjusted, the frame 32 being slid to the right or to the left in Fig. 8, the fingers 37 moving in the slots 36. Securing devices, such as nuts 45 are threaded on the fingers 37, and by tightening the nuts, the frame 32 is held in any position to which it may have been adjusted laterally, the top and bottom flanges 33 being bound between the nuts 45 and the arms 38.

Figure 11 makes it clear that the filler for any of the barriers described may be made in any desired way. For instance, filler 46 may be cane or stamped imitation cane, secured to the barrier frame 41.

In Figs. 12, 13, 14 and 15, parts hereinbefore described have been designated by numerals previously used.

The modifications are as follows: the filler 100 may be made of expanded metal, spot welded at 101, or connected otherwise, to the frame 32b. The hinge pintles 40b are mounted in angle brackets 102, which may be attached by securing elements 103 to the window frame. There are abutments 104 on the fingers 37b, and the flanges 33b are bound between the abutments 104 and the nuts 45b. In Figs. 12, 13 and 14, parts here-

inbefore described have been designated by numerals previously used, with the suffix "b".

In Figs. 16 and 17, parts hereinbefore described have been designated by numerals previously used, with the suffix "c".

The structure shown in Figs. 16 and 17 is very much like the structure shown in Figs. 12, 13, 14 and 15, aside from the fact that the elongated slots 36b of Figs. 12 and 13 have been replaced by holes 105 in which the fingers 37c are closely received.

Having thus described the invention, what is claimed is:

1. In a device of the class described, outer barriers, means for hinging the said barriers at their outer edges to the sides of a window frame, near to the lower end of the frame, inner barriers hinged to the inner edges of the outer barriers, and a releasable connection between the inner edges of the respective inner barriers, the hinging means constituting mechanism for locating all of the barriers outwardly of a window curtain, to prevent the curtain from blowing outwardly through a window frame.

2. A barrier of the class described comprising oppositely-disposed U-shaped members having their ends overlapped for relative sliding movement, means for holding the upper ends of said members together, means for holding the lower ends of said members together, the members of the barrier having openings, and a filler laced through the openings, the laced construction of the filler providing for an expansion and a contraction of the barrier.

3. A barrier of the class described comprising U-shaped members having their upper and lower ends overlapped to provide for a lateral expansion and contraction of the barrier, a holding device joining the upper ends of said members, a holding device joining the lower ends of said members, and a combined ornament and reenforcement on the top of the barrier, and held in place by the first-specified holding member, the upper portion of the barrier having an elongated slot for the reception of the said holding member, whereby the ornament and reenforcement may be adjusted transversely of the barrier, to dispose the ornament and reenforcement symmetrically with respect to the barrier.

4. A barrier comprising a frame provided in its top and in its bottom with elongated slots, arms within the barrier and extended outwardly beyond one edge of the barrier, the arms having fingers which are adjustable in the slots, holding devices on the fingers and engaging the frame, hanger means whereunto the outer ends of the arms are pivoted, and an extension detachably mounted on the arms, between the hanger means and the frame.

5. A barrier comprising a frame provided in its top and in its bottom with openings, arms within the barrier and extended outwardly beyond one edge of the barrier, the arms having fingers received in the openings, holding devices on the fingers and engaging the frame, and hanger means whereunto the outer ends of the arms are pivoted.

AGNES JUELSON.
